WINDOW REGULATOR ATTACHMENT

Herbert C. Field, Windsor, Ontario, Canada, assignor to Ternstedt Manufacturing Company, Detroit, Mich., a corporation of Michigan

Application December 6, 1932, Serial No. 645,970

14 Claims. (Cl. 268—126)

This invention relates to a window regulator attachment for operatively connecting the window regulator to the window.

In the assembly of an automotive vehicle body it is highly desirable to assemble the window in the window opening after the lock board with the lock and window regulator mechanism has been secured in place in the window well and the upholstering or trimming of the interior of the body has been completed. This is possible where the upright edges of the window are parallel and run in parallel window channel guideways. Usually the lower sash of the window is provided with a bracket having an elongated slot with an enlarged opening at one end and the regulator arm carries a lift pin having an enlarged head which engages in the slot. In assembling the window panel in the window opening the regulator arm is first raised slightly above the normal raised position so that the window can be tilted into the window opening with the lift pin engaging in the enlarged opening in the sash bracket. The window regulator is then turned down and as it is turned down the window is swung into vertical position and the lift pin passes from the enlarged opening into the narrow elongated slot. Thereafter the garnish moulding is fixed in the window opening. As the window is raised and lowered the lift pin travels only in the elongated portion of the slot thus assuring the continuity of engagement between the window regulator and the window. In removing this type of window it is merely necessary to lower the window glass, remove the glass runs and the garnish moulding, raise the window to substantially closed position, then tilt the window inwardly of the body, raise the window regulator somewhat above the normal raised position it assumes when the panel is fully raised whereupon the lift pin travels from the elongated slot into the enlarged opening thus permitting the window to be disconnected from the regulator lift pin. This method of connecting the window to, and disconnecting it from, the window regulator is not very practical where a two-point suspension regulator is used. This type of regulator is usually used where the upright edges of the window panel are not parallel, i. e. where the one upright edge is inclined relative to the other because the inclined edge permits the window to tilt or cock edgewise in the glass runs and therefore requires a two-point or balanced lift for the window. This inclination of one of the upright edges of the window panel usually occurs where the front door pillar has an angular slope and

pillar slopes at the top. Where a two-point suspension regulator is used there are two lift pins instead of one, and the window sash carries two slotted sash brackets, one for each of the lift pins. With such a two-point suspension regulator it is difficult to engage each of the lift pins with its sash bracket in the manner above described.

Hence, it is an object of this invention to obviate this difficulty and produce a regulator with a multiple point suspension which will permit the regulator to be easily attached to the window.

This invention contemplates as a further object an attachment between the window and the window regulator that will permit the window glass to be rotatable in and out or hinged mounted when installed in the body.

It is an object of this invention to produce an attachment for securing a window to a window regulator in the form of a hinge, the members of which have a sliding, disconnectable interengagement.

It is a further object of this invention to produce an attachment between the window and the window regulator that will permit the window to be attached or detached from the window regulator simply by tilting the window inwardly of the body after the garnish moulding has been removed and the window raised somewhat above its normal window closing position.

This invention also contemplates an attachment between the window and the window regulator which is noiseless in operation having a novel sliding contact surface as it moves relative to the window during the raising and lowering of the same.

A further feature of this invention is that the regulator attachment is noiseless in operation and it has no appreciable amount of lost motion.

In the drawings:

Figure 1 is an elevation of a portion of a vehicle body showing a window opening defined on one side by a sloping pillar and closed by a window panel which is operatively connected to the regulator by the new type of roll-in attachment.

Figure 2 is a section along the line 2—2 of Figure 1.

Figure 3 is a detail section through the attaching plate and regulator arms showing the window being tilted inwardly and disconnected from the regulator.

Figure 4 is a detail of the regulator arms and attaching plate.

Figure 5 is a section along the line 5—5 of Figure 4.

Figure 6 is a detail section showing the window rotated to attaching or detaching position.

Figure 7 is a detail of the felt retainer.

Referring more particularly to the drawings there is shown, by way of example, a portion of a vehicle body which is a door 1 having a window opening 2. The window opening 2 is closed by the window panel 3 which is slidably upwardly and downwardly in the window channel guide-ways 4 and 5. It will be noted that the upper portion of the front door pillar 6 has an angular slope. To conform to the angular slope of the pillar 6, the front upright edge 7 of the panel 3 likewise has an angular slope, that is, it is inclined relative to the rear upright edge 8 of the panel 3. The inside periphery of the window opening 2 is defined by the garnish moulding 9. The upper and side edges of the window, when in raised position, are sealed by the channel strip 10 having the upstanding pile lining 11 which engages and seals the edge of the panel. The pile lined channel 10 extends around the sides and top of the window opening and serves both as a window guideway and header strip. The window guide channel lining 11, as shown, may be made from a stiff pile vulcanized in rubber base. The channel member 10 is held in place between the reveal 12 and the garnish moulding.

The bottom edge of the window is provided with any suitable window sash channel 13. The window is arranged to be raised and lowered by any suitable window regulator such as the planograph type shown which briefly comprises a stamped gear sector 14 provided with a lifting arm 15. The sector may be driven by any well-known means such as the well-known crank and pinion (not shown). The lifting arm 15 is supplemented by a check link 16 which has a pivotal connection (not shown) with the regulator support plate 17. In this type of planograph or check link regulator the arms 15 and 16 are pivoted to the attachment plate 18 and due to their planograph action maintain the plate 18 horizontal and consequently keep the window from cocking and binding in the guides 4 and 5 as it is raised and lowered.

The instant invention concerns the attachment between the regulator and the window. The attachment herein takes the form of the plate 18 to which the arms 15 and 16 are pivoted as at 19 and 20, respectively. The upper edge of the plate 18 is rolled back upon itself as at 21 so that the edge 22 of the rolled-over portion 21 is spaced from the face of the plate 18 to form the gap 23 (Figure 5). The upper face 24 of the rolled back portion 21 is preferably, although not necessarily, formed so that in section it is a semi-circle having its center at 25. The lower face 26 of the rolled-over portion 21 in section is likewise preferably a semi-circle having its center as at 27. The rolled-over edge 21 in a sense forms a somewhat flattened elongated tube having a lengthwise slot 23 and its axis extending parallel to the lower edge of the window panel 3. It will be noted (Figure 5) that the vertical or up and down diameter of the rolled-over portion 21 is longer than the horizontal or transverse diameter for reasons which will be explained below.

Inasmuch as the tubular portion 21 of the plate 18 is arranged to travel back and forth in the track 28 as the window is raised and lowered, and inasmuch as it is desirable to prevent rattles between the track and the attaching plate and to reduce the friction between these two members, to this end a suitable surface of friction reducing

and noise preventing material is preferably interposed between the rolled-over edge 21 and the track 28. Preferably this material comprises a layer of felt 33 impregnated with lubricant secured to the outer surface of the plate 18. To secure the felt 33 to the plate 18, one of the edges of the felt is folded around a cord 50 and stitched as at 34 to form a pleat extending lengthwise of the sheet of felt. The diameter of this pleat is somewhat greater than the gap 23 between the rolled-over edge 21 and the adjacent face of the plate 18. Hence, the pleat is slid lengthwise through the hollow inside of the tubular portion 21 of the plate 18 and the web portion of felt then wound around the outer face of the tubular portion 21. The plate 18 is provided with the transverse groove 35. Suitable tooth shaped lugs 38 are struck perpendicularly from the plate 18 adjacent the V-groove 35 before the felt is assembled thereto, as shown in the dotted lines. After the pleat has been inserted in the rolled-over portion 21, as above described, and the felt wrapped over the rolled-over portion, the free edge of the web portion of the felt is impaled upon the pointed lugs 38 and inserted in the V-groove 35. A V-shaped felt retainer 37 is then inserted in the groove over the free edge of the felt and the pointed lugs 38 and round lugs 51 bent over into engagement with the outer edge of the felt retainer 37 thus securely clamping the felt between the retainer and the V-groove.

Since, obviously, if the window is raised and lowered the attachment plate 18 must travel back and forth along the lower edge of the window and since it is an object of the invention to make the window freely rotatable in and out of the window opening about its regulator support, to this end the sash channel 13 has spot welded or otherwise suitably fixed thereto a track 28. The track 28 roughly comprises an upper lip 29 which is flat and secured to the sash channel 13 and a lower lip 30 which is preferably curved about a true radius and cooperates with lip 29 to form a socket for the rolled-over edge 21 of plate 18. It will be noted that the edge 31 of the lip 30 is spaced from the flat upper lip 29 to produce the slot 32. This slot 32, that is, the distance between the edge 31 of the lip 30 and the lip 29, is greater than the short or transverse diameter of the rolled-over portion 21 of the plate 18, but this slot or distance is somewhat less than the overall long diameter of the portion 21 in conjunction with its felt covering 33. Hence, as shown in Figure 3, the window is free to rotate in and out within limits without the plate 18 becoming detached from the track 28, but if the window is tilted inwardly (the garnish moulding and channel guide first being removed) a sufficient distance the track 28 rotates about the rolled-over edge portion 21 until the track reaches a position relative to the rolled-over edge 21 where the slot 32 is equal to or greater than the diameter of the felt covered rolled-over edge 21 thus causing the track 28 to be disengaged from the attaching plate 18.

From the above description it is obvious that the attachment between the window and the window regulator permits the window to be freely rotatable in and out, that is, as viewed in Figures 2, 3 and 6, the window 3 is not only free within limits to swing inwardly of the body in a counter-clockwise direction but likewise outwardly in a clockwise direction about the felt surfaced tubular portion 21 of the plate 18 as an axis. The extent of this swing as the window

is raised or lowered, of course, is determined by the relative position of the guide channels 11 and regulator. Because the window is free to fulcrum about the rolled-over edge 21 of the 5 attaching plate 18, the travel of the window panel 3 in a plane not parallel or somewhat inclined to the plane in which the regulator arms and attaching plate 18 travel in their up and down movement will prevent any binding between the 10 window panel and the regulator.

When it is desired to disconnect the window from the regulator one need only lower the window, remove the garnish moulding 9 and channel guide 11, then raise the same. At this 15 time the window may be tilted inwardly of the car, after raising the same slightly above the normal raised position, until the slot 32 of the track 28 rotates to a position about the felt covered rolled edge 21 where the slot 32 is equal to 20 or greater than the diameter of this rolled edge of the plate 18 (Figure 6) whereupon the window can be withdrawn from the opening. It will be noted that with this type of roll-in attachment there is no need to remove the lock 25 board 39 or the trim upholstery to permit installation or removal of the window panel.

It will be noted from Figure 1 that as the plate 18 travels back and forth in the track 28 as the window is raised and lowered, the center of the lower edge of the window panel 3 will always be some place between the ends of the tubular portion 21 of the plate 18. In other words, the tubular portion 21 of the plate 18 provides a multiple point suspension for the window and in 35 all positions of the window supports the same on both sides of the center of its bottom edge thus preventing the window from cocking in its guides 4 and 5.

I claim:

40 1. In a window assembly having an opening, a panel for the same, and a regulator for raising and lowering the panel to close and open the window opening, an attachment for attaching the window to the regulator comprising in combination a track member and a slide member, one of said members being secured to the window panel and the other to the regulator, the said slide and track members having a sliding, hinging interengagement whereby the window is free to fulcrum relative to the regulator inwardly and outwardly during the normal operation of the regulator to raise and lower the window and also at assembly or disassembly.

55 2. In a window assembly having an opening, a panel for the same, and a regulator for raising and lowering the panel to open and close the window opening, an attachment for attaching the window panel to the regulator comprising in combination a track member having an elongated slot, and a slide member, one of said members being secured to the window panel and the other to the regulator, the said slide member having a slidably hinging interengagement with the track member through the said slot whereby the window is free to fulcrum relative to the regulator both during the normal operation of the regulator to raise and lower the window and at assembly or disassembly of the regulator and window.

70 3. In a window assembly having a window panel and a regulator for moving the window panel to open and closed positions, an attachment for attaching the window panel to the regulator comprising a pair of hinged members, one of said members being secured to the lower edge of the

panel and the other to the regulator, the said hinged members having a hinging interengagement during the normal operation of the regulator at multiple points on both sides of the center of the lower edge of the panel and being disconnectable without flexing said member within limits as the one is rotated about the other at assembly or disassembly.

4. In a window assembly having a window panel, guides for the said panel, and a regulator of the planograph type for moving the window panel along the said guides to open and closed position, an attachment for attaching the window panel to the regulator comprising a pair of hinged members, one of said members being fixed to the lower edge of the panel and the other of said members being pivoted to the arms of the said regulator, the hinged members having a hinging interengagement during the normal operation of the regulator at multiple points on each side of the center line of the lower edge of the window panel whereby the panel is held against edgewise cocking in the guides and is free to fulcrum about its lower edge during the raising and lowering of the window and also at assembly or disassembly.

5. In a window assembly having an opening, a panel for the same, and a regulator for raising and lowering the panel to open and close the window opening, an attachment for attaching the panel to the regulator comprising in combination a track member in the form of a socket having an elongated slot, and a slide member having a long diameter greater than the width of the slot and a short diameter less than the width of the slot, one of said members being secured to the panel and the other to the regulator, the said slide member having a slidably, hinging interengagement through the slot with the said track member whereby the window panel is free to fulcrum relative to the regulator.

6. In a window assembly having an opening, a panel for the same, and a regulator for raising and lowering the window panel to open and close the window opening, an attachment for attaching the window panel to the regulator comprising in combination a track member in the form of an elongated socket, and a member having a tubular portion slidably and hingedly interengaging the track member through the said slot, one of said members being secured to the window panel and the other to the regulator, the tubular portion of the said member having a long diameter greater than the width of the slot and a short diameter less than the width of the slot whereby the panel may be disconnected from the regulator by rotating the same until the track reaches a position relative to the tubular portion of the slide member where the width of the slot is greater than the diameter of the tubular portion.

7. In a window regulator assembly the combination of a window guide, a window panel guided in the said guide, a garnish moulding which can be removed to permit the window to tilt inwardly, a window regulator for sliding the panel in the guide, a track member having an elongated slot, and a slide member insertable through the slot having a sliding, hinging engagement with the track, one of said members being secured to the window regulator and the other to the window panel, the said slide member having a long diameter greater than the width of the slot and a short diameter less than the width of the slot whereby when the garnish moulding is removed the window can be tilted

until the track reaches a position relative to the said slide member where the width of the slot is greater than the diameter of the slide to permit the track to be disconnected from the slide member thus disassembling the window panel from the window regulator.

8. In a window assembly having an opening, a panel for the same, and a regulator for raising and lowering the panel to open and close the window opening, an attachment for attaching the window panel to the regulator comprising in combination a track member in the form of an elongated, arcuate socket, and a slide member having an edge rolled back upon itself to form a tubular slide, one of said members being secured to the lower edge of the window panel and the other to the regulator, the said slide and track members having a sliding, hinging interengagement whereby the window panel is free to fulcrum about its lower edge.

9. In a window assembly having an opening, a panel for the same, and a regulator for raising and lowering the panel for opening and closing the window opening, an attachment for attaching the window panel to the regulator comprising a track member and a slide member, one of said members being secured to the window panel and the other to the regulator, the said slide member having an elongated slot, and a web of fibrous material having an interlocking engagement with the slide member in the said slot and drawn about the said slide and slidably engaging the track member.

10. In a window assembly having a window panel, and a regulator for moving the window panel to open and closed position, an attachment for attaching the window panel to the regulator comprising a pair of hingedly interengaged members, one of said members being secured to the lower edge of the panel and the other to the regulator, one of said members having an elongated slot, and a web of felt in interlocking engagement in the said slot and drawn over the face of the said member to form a noise preventing surface between the hinged members.

11. An attachment for securing the window regulator to a window panel comprising in combination a pair of hinged members, one of said members arranged to be secured to the lower edge of the window panel and the other to the regulator, one of said members having an edge rolled back upon itself to form a slot, and a web of felt having a pleated end, the said pleated end of the web of felt having an interlocking engagement with the rolled-over edge of the said mem-

ber and being drawn about the outer surface of the said member to interpose a felt surface between the hingedly interengaged members.

12. In a window assembly having an opening, a panel for the same and a regulator for raising and lowering the panel to close and open the window opening, an attachment for attaching the window to the regulator comprising in combination a track member and a slide member, one of said members being secured laterally along the lower edge of the window panel and the other to the regulator, the said slide and track members having a laterally rigid, sliding, hinging interconnection during the normal operation of the regulator whereby the window is free to fulcrum about its lower edge as the window is raised and lowered and at assembly or disassembly.

13. In a window assembly having an opening, a panel for the same and a regulator for raising and lowering the panel for closing and opening the window opening, an attachment for attaching the window panel to the regulator comprising a track member having an elongated slot and a slide member, one of said members being secured to the window panel and the other to the regulator, the said slide member having a slidable hinging interengagement with the track member through the said slot whereby the window is free to fulcrum relative to the regulator both during the normal operation of the regulator to raise and lower the window panel and at assembly or disassembly, and a web of distortable friction reducing material mounted on one of said members and slidably engaging the other of said members.

14. In a window assembly having an opening, a panel for the same, and a regulator for raising and lowering the panel to close and open the window opening, an attachment for attaching the window to the regulator comprising in combination a track member and a slide member, one of said members being secured to the window panel and the other to the regulator, the said slide and track members having a sliding, hinging interengagement whereby the window is free to fulcrum relative to the regulator inwardly and outwardly during the normal operation of the regulator to raise and lower the window and also at assembly or disassembly, and a surface of distortable friction reducing material mounted on one of said members and slidably engaging the other of said members.
